US00D488965S

(12) **United States Design Patent**
Schuler

(10) Patent No.: US D488,965 S
(45) Date of Patent: ** Apr. 27, 2004

(54) CARRYING TRAY FOR BEVERAGE CONTAINERS

3,478,457	A	*	11/1969	Watkins	.....	211/75
D381,515	S	*	7/1997	Haynes	.....	D7/553.4
D447,916	S	*	9/2001	Bodum	.....	D7/706

(76) Inventor: **Troy Schuler**, 10301 S. Bridge Dr.,
Alta Loma, CA (US) 91737

* cited by examiner

(**) Term: 14 Years

Primary Examiner—Terry A. Wallace

(21) Appl. No.: 29/174,013

(22) Filed: Jan. 19, 2003

(51) LOC (7) Cl. 07-06

(51) EOC (7) Cl. 07-00
(52) U.S. Cl. D7/706; D7/553.4

(52) U.S. Cl. D7/700, D7/550.1
 (58) **Field of Search** D7/701, 705-708,
 D7/550.1, 552.1, 553.1-553.5, 554.1, 554.3,
 590, 600; 206/557, 558, 562-564; 211/71.01,
 74, 75, 126.1, 126.14; 248/311.2
